UNITED STATES PATENT OFFICE.

JACOB SEYMOUR BURTON, OF MELVERN, KANSAS.

WOVEN-WIRE-FENCE FABRIC.

SPECIFICATION forming part of Letters Patent No. 623,765, dated April 25, 1899.

Application filed June 30, 1898. Serial No. 684,839. (No model.)

To all whom it may concern:

Be it known that I, JACOB SEYMOUR BURTON, a citizen of the United States, residing at Melvern, in the county of Osage and State 5 of Kansas, have invented a new and useful Woven-Wire-Fence Fabric, of which the following is a specification.

This invention relates to woven-wire-fence fabrics; and it has for its object to provide a 10 new and useful form of fabric so woven as to obviate slipping of the wires, whereby the fabric will maintain its rigidity and shape at all times.

A further object of the invention is to provide a novel construction of wire-fence fabric having the wires thereof woven together in such a manner as to greatly economize in the amount of wire required to build the fence, 15 while at the same time preventing the wires 20 from doubling up during the process of weaving.

With these and other objects in view, which will readily appear as the nature of the invention is better understood, the same consists in the novel construction, combination, 25 and arrangement of parts hereinafter more fully described, illustrated, and claimed.

In the accompanying drawings, Figure 1 is an elevation or plan view of a section of woven-wire-fence fabric constructed in accordance 30 with this invention. Fig. 2 is a view similar to Fig. 1, showing the fence partially completed to illustrate the relation of the different wires forming the fabric. Fig. 3 is a detail elevation or plan view showing the intermediate filling-wires in dotted lines to illustrate the form or shape of the selvage weft-wires, which are twisted on the straight selvage line-wires. Fig. 4 is a detail view showing 35 a modification in which the continuous cabling or twisting 4^a is dispensed with and the terminals of each mesh-loop 3 are twisted a few times around the selvage-wire.

Referring to the accompanying drawings, 40 the numerals 11 designate oppositely-located parallel straight selvage-wires running longitudinally of the fence fabric and made of smooth or barbed wire, as preferred.

During the process of weaving the fence 45 fabric the straight selvage-wires 1 are strung out to form supporting-wires, upon which the body of the fabric is worked, and in order

that the precise construction of the fabric may be fully understood reference is first made to the selvage weft-wires 2, which are 55 arranged along the selvage line-wires 1, as plainly illustrated in diagrammatic Figs. 2 and 3 of the drawings. The said selvage weft-wires 2, during the process of weaving the fence, are bent to form a continuous series of 60 substantially rectangular disconnected mesh-loops 3, which are spaced at regular intervals apart and are of a uniform size in order to give a symmetrical appearance to the fence fabric, and the portions of the selvage weft-wires 2 between the spaced mesh-loops 3 are 65 twisted or wrapped around the selvage-wires, as at 4^a , to provide a firm connection between the said weft-wires 2 and the selvage line-wires 1. 70

During the weaving of the fence fabric between the selvage line-wires 1 intermediate filling-wires 4 are carried along with the selvage weft-wires 2, and these intermediate filling-wires 4 in the operation of weaving are 75 formed with continuous substantially right-angled bends, whose horizontal portions 5 bridge the spaces between and connect the spaced mesh-loops 3 of the selvage weft-wires at the corners of the latter, as plainly illustrated in Fig. 2 of the drawings. The said horizontal portions 5 of the intermediate filling wires 4 also bridge the space between the disconnected corners of each other, as also illustrated in Fig. 2 of the drawings, and at 80 the points where the said selvage weft and filling wires intersect said wires are closely cabled or twisted together by a plurality of 85 twists to provide for firmly interlocking the meshes of the fabric without the use of continuous straight longitudinal strand or line wires, such as are commonly employed in the 90 construction of woven-wire-fence fabric.

While the shape and relation of the selvage weft and filling wires have been described 95 separately, it will be understood that these wires are bent into shape and twisted together as the weaving progresses between the selvage line-wires 1.

It is not essential that the disconnected rectangular mesh-loops 3 be formed from a continuous wire having the continuous cabling or twisting 4^a around the selvage-wires, as this construction may be modified, as shown 100

in detail Fig. 4 of the drawings. In this figure of the drawings is illustrated a construction in which the continuous cabling or twisting 4^a is dispensed with and the terminals of each mesh-loop 3 are twisted only a few times around the selvage-wire, as at 4^b. In other respects the construction of the fabric is precisely the same as already described, and I will have it understood that changes in the form, proportion, and the minor details of construction may be resorted to without departing from the principle or sacrificing any of the advantages of this invention.

Having thus described the invention, what is claimed as new, and desired to be secured by Letters Patent, is—

A woven-wire-fence fabric, comprising opposite parallel straight selvage line-wires, selvage weft-wires twisted onto the line-wires, and bent at one side of the latter to form a

continuous series of substantially rectangular mesh-loops, and intermediate filling-wires having continuous substantially right-angular bends, whose horizontal portions connect the mesh-loops of the selvage weft-wires, and also bridge the space between and connect the disconnected corners of each other, said selvage weft and filling wires being closely cabled together by a plurality of twists at their points of intersection, to interlock the meshes without the use of straight longitudinal strand or line wires, substantially as set forth.

In testimony that I claim the foregoing as my own I have hereto affixed my signature in the presence of two witnesses.

JACOB SEYMOUR BURTON.
